UNITED STATES PATENT OFFICE

EDWARD J. FOWLER, DECEASED, LATE OF REDWOOD CITY, CALIFORNIA, BY EDITH MARY FOWLER, EXECUTRIX, OF REDWOOD CITY, CALIFORNIA, AND DUDLEY BAIRD, OF BERKELEY, CALIFORNIA, ASSIGNS TO NICHOLS COPPER COMPANY, OF NEW YORK, N. Y., A CORPORATION OF NEW YORK

ROASTING FURNACE

Application filed January 24, 1928. Serial No. 249,134.

This invention relates to roasting furnaces, the invention in one of its adaptations being particularly applicable to furnaces for laboratory use.

6 The objects of the invention include the provision of a furnace of the class indicated which will be dependable, relatively simple and efficient in operation under various conditions, and in which the treatment of various kinds of materials may be accurately controlled.

15 Various further and more specific objects, features and advantages will clearly appear from the detailed description given below taken in connection with the accompanying drawings which form a part of this specification and illustrate, merely by way of example, one embodiment of the invention.

20 The invention consists in such novel features, arrangements and combinations as may be shown and described in connection with the furnace herein disclosed by way of example only, and as illustrative of a preferred embodiment, together with certain novel methods and steps of processes as may be described herein.

25 In the drawings, Fig. 1 is a vertical sectional view through a furnace comprising one embodiment of the invention;

30 Fig. 2 is a vertical sectional view partly broken away taken substantially at right angles to the section of Fig. 1; and

35 Fig. 3 is a top plan view of the same furnace.

40 In the particular furnace shown in the drawings, a single hearth may be provided as at 10 comprising a circular plate of metal, the metal preferably being capable of withstanding unusually high temperatures without deterioration or warping. A metal known in the trade as "Pyrocast" is found to be satisfactory for this purpose. Such a hearth plate offers a smooth area over which the ore or other material under treatment may be uniformly rabbled without danger of contamination resulting from deterioration or wearing of the hearth as would occur if brick, tile or the like material were used in accordance with the more common practice.

45 The hearth is preferably enclosed by a

relatively thick wall of durable heat insulating material as at 11. A mixture well known in the trade as "Celite" carefully rammed in place has been found to be suitable for this purpose. An outer protective shell of sheet steel may be provided as at 12. The top of the enclosure may comprise a body of the heat insulating material as at 13 secured within a cover member 14 which in turn may be hinged as at 15 to the shell member 12. Such a hinge cover permits the furnace to be conveniently opened for inspection and also for removal, repair or replacement of rabbling mechanism and heating devices as will be hereinafter described. Eye bolts as 16 at 16 may be provided to facilitate lifting the cover member.

50 The entire furnace in the form shown may be supported in an elevated position upon a cast iron table member 17 having supporting legs as at 18, the hearth 10 being secured to the table member by screws 19 passing down from the hearth through the insulating material. Such a supporting table offers a means for suspending suitable rabbles driving mechanism beneath the furnace in a position facilitating adjustments or other necessary attention. Furthermore, the table provides a means for supporting the furnace out of direct contact with laboratory 55 benches and the like and also permits air or other fluid medium acting in the furnace upon the material under treatment to be admitted at desired points through passages, as hereinafter described.

60 At the middle of the hearth a substantially vertically extending rotatable shaft may be provided as at 20 carried in a single bearing 21 of extended area formed integrally with the table member 17. At its upper end the shaft 20 may be formed with a seating portion 22 extending transversely of the shaft for receiving a rabbble supporting member 23, which may comprise a bar of rectangular cross-section formed of nichrome steel or other suitable material, its ends extending substantially horizontally in opposite directions over the hearth. Cast iron or other tubular members or sleeves as at 24 and 25 65 may be slidably received upon the ends of

the bar 23 and each integrally formed with a plurality of rabble teeth as at 26 and 27 respectively. These tubular members, together with the rabble teeth, may be detachably secured on the bar 23 in a simple manner by the use of pins as at 28 passing down through aligned apertures in the bar and tubular members as shown. It will be noted that the rabble teeth 26 and 27 respectively are oppositely directed. That is, with the shaft 20 rotating in a given direction, the teeth 26, for example, will tend to deflect the material under treatment on the hearth toward the center of the hearth, whereas at the same time the rabble teeth 27 will tend to deflect such material toward the periphery of the hearth. Consequently, the material is substantially uniformly rabble, first inwardly and then outwardly of the hearth.

At one side of the furnace a door as at 29 may be provided, a corresponding opening 30 being formed in the insulating material of the furnace wall. The material to be treated in the furnace may be introduced either by opening the cover of the furnace or through the door 29 on to the hearth. A large brick or other stopping means as at 31 is then placed in the opening 30 and the treatment may then be started. After the treatment is completed, the door 29 may be opened, and the brick removed, whereupon one of the rabble retaining pins 28 may be removed so as to permit removal of the tubular member 24 having rabble teeth which move the ore toward the center of the hearth. Then when the shaft 20 is rotated, the rabble teeth 27 will gradually move the material outwardly of the hearth and the material may be discharged through an opening 32 at the periphery of the hearth. The opening 32 may be normally closed by a plug member 33, the plug member being normally held in position with its face in the plane of the hearth surface by a control lever 34 engaging the plug member as at 35 whereby, upon turning the handle portion 36, the plug may be allowed to drop from the normal position as shown, permitting the ore to be discharged as it is raked toward the opening by the rabble teeth 27. After the furnace is discharged, the rabble member 24 may of course be readily restored in place and secured by its pin member 28.

The shaft 20 is preferably formed with a longitudinal cavity 37 as shown and through this cavity an adjusting rod 38 may extend permitting adjustment of the height of the rabble teeth from a point outside the furnace. The upper end of the rod 38 engages at 39 the rabble supporting bar 23 and also may be slidably received within a bearing portion at 40. The lower end of the rod 38 may be slidably received within a bearing portion 41 and the vertical position of the rod in respect to the shaft 20 may be ad-

justed by a screw 42 threaded through the lower end of the shaft 20. With this construction the height of the rabble supporting bar 23, as well as the rabble teeth, in respect to the hearth and rotating shaft, may be accurately adjusted without opening the furnace, merely by turning the screw 42. In order to limit the upward movement of the supporting bar 23 and to securely grip the same, removable shims 43 may be inserted between the bar and the top portion 44 of the shaft member 20.

Air ports may be provided as at 45 leading into the cavity 37 and at the upper end of the shaft the cavity 37 communicates with the space within the furnace by way of passages 46 and the space 47 beneath the supporting arm 23. The amount of air admitted through these passages may be adjusted by an air shutter member 48 encircling the shaft 20 at the ports 45.

Supplementing the air passages above described, further passages may be provided as at 49 outside the bearing 21 and communicating with the interior of the furnace through openings as at 50. The passages 49 may be utilized not only to admit air but other fluid mediums as may be desired to carry on the reactions within the furnace. The quantity of fluid admitted at 49 may be adjusted as by a butterfly valve 51 having a set screw as at 52. The passages 37 and 49 permit a cooling fluid to come into contact with the bearing 21 both interiorly and exteriorly, thus insuring the bearing and the other parts beneath the furnace against overheating. The passages also make available the air or other fluid within the furnace at points where the rabbling action takes place, thus insuring a rapid and efficient treatment.

The furnace may be heated by a gas or oil torch or if desired, electrically. If a torch is to be used, the same may be admitted through an opening as at 53.

One form of an electrically energized heating means is illustrated in Fig. 1 and may comprise an insulating plate 54 having detachable supporting means as at 55 secured to the cover member 14. Within the lower face of the insulating plate 54 a spirally formed electrical resistance member 56 may be secured and provided with leading-in wires as at 57 and 58 passing through suitable insulators 59 within the cover member. A detachable electrically energized heating means is thus provided extending over the major portion of the hearth area and yet if desired, the same may be readily removed to permit firing of the furnace by a torch or other heating medium. The resistance member 56 is preferably made of a relatively large cross-section in order that the same may be durable and effective in operation. With a resistance member of such cross-section and of convenient length, it is desirable

to provide a source of current having a voltage in the general neighborhood of 20 to 35 volts and where the furnace is to be applied to experimental uses, it is desirable to provide a suitable transformer permitting current of this voltage to be taken from the commercial power circuits. In order that the furnace temperatures may be readily controlled, a suitable variable resistance may be inserted in the source of current supply as will readily be understood.

One form of driving mechanism for the shaft 20 will now be described. A suitable variable speed motor 60 may be suspended in adjustable position from beneath the table 17 and connected to suitable reduction gearing as at 61. The gearing at 61 may comprise a shaft 62 driven by a pulley 63 connected by a belt 64 with the motor. A suitable pinion and gear may be positioned within an enclosure 65 for driving a shaft 66 carrying a pinion 67, which in turn engages a driving gear 68 mounted upon the shaft 20. The driving gear 68 may be protected by a guard member 69. It is highly desirable to provide the enclosure 65 for the pinion and gear therein in order that the same will not be interfered with by dust and particles of material under treatment as discharged from the furnace. The motor 60 may be accompanied by any suitable and well-known form of speed regulating and adjusting means to enable the operator to control the rate of rabbling by the rabble teeth.

At the top of the furnace, an opening and stack may be provided as at 70 and a discharge of gases therethrough may be regulated as by a damper 71. The stack may be of sufficient height to cause a substantial draft to be created through the furnace for proper admission of air.

The bearing 21 may be lubricated by the use of a suitable grease cup 72 in communication therewith.

Provision may be made as at 73 for inserting a pyrometer through the furnace wall.

Although the furnace as above described is particularly applicable, according to one phase of the invention, to uses as a laboratory furnace, it will be understood that many features of the invention are also adaptable commercially to the reduction of quantities of ore or the treatment of other materials, for example, the roasting of calcium, the drying, revivifying or heating of various materials, including ores, minerals, earth, and vegetable or animal compounds.

The furnace above described is particularly adaptable to a wide variety of operations, since the temperatures therein and the amount of air admitted may be widely varied, and the rabbling action may also be controlled not only by the adjustment of the speed of rotation of the shaft 20, but also

by adjustment of the height of the rabble teeth.

While the invention has been described in detail with respect to a particular preferred example thereof which gives satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent of the United States is:

1. In a roasting furnace, a hearth, a rotatable substantially vertically extending shaft carrying a rabble arm, located over said hearth within the furnace, and means extending longitudinally of said shaft to the exterior of the furnace for effecting vertical adjustment of the rabble arm in respect to said shaft.

2. In a roasting furnace, a hearth, a rotatable substantially vertically extending shaft carrying a rabble arm, located over said hearth within the furnace, and means extending longitudinally of said shaft to the exterior of the furnace for effecting vertical adjustment of the rabble arm in respect to said shaft, said shaft being also formed with a longitudinally extending passage for conducting a fluid into the furnace.

3. A roasting furnace comprising a hearth within a heat insulating enclosure, a table for supporting the same in elevated position, a rabble arm and a rotatable shaft therefor extending vertically up through said table and hearth, a bearing mounted on said table and normally comprising the sole supporting means for said shaft, and passages extending interiorly of said bearing and exteriorly thereof through said hearth for admitting fluid to the furnace.

4. A roasting furnace comprising a hearth within a heat insulating enclosure, a table for supporting the same in elevated position, a rabble arm and a rotatable shaft therefor extending vertically up through said table and hearth, a bearing mounted on said table and normally comprising the sole supporting means for said shaft, passages extending interiorly of said bearing and exteriorly thereof through said hearth for admitting fluid to the furnace, and independent means for adjusting the flow of fluid respectively through said passages.

5. In a roasting furnace a hearth, a vertically extending rotary rabble arm shaft having a transversely extending seating portion for receiving a rabble arm, a rod extending downwardly through the shaft from said seating portion to the exterior of the furnace, means for adjusting the vertical position of

said rod, the upper end of which is adapted to be engaged by and to support the rabble arm over said hearth, and a passage surrounding said rod within the shaft for admitting gas into the furnace.

5 6. In a roasting furnace, a hearth therein, a vertically extending rotary rabble arm shaft having a transversely extending seating portion for receiving and supporting a rabble arm located over said hearth, a rod extending downwardly through the shaft from said seating portion to the exterior of the furnace, means for adjusting the vertical position of said rod, the upper end of which is adapted to be engaged by and to support the rabble arm, and means over said seating portion for limiting upward movement of the rabble arm.

10 7. In a roasting furnace, a hearth therein, a vertical rotary rabble arm shaft, a bearing at the under side of the furnace for carrying the weight of said shaft, a rabble arm within the furnace carried by said shaft and located over said hearth, and means operable from the under side of the furnace for adjusting the elevation of said rabble arm in respect to said shaft.

15 8. In a roasting furnace, a hearth therein, a rabble construction comprising a supporting arm located over said hearth, a tubular member slidably received on said arm and embracing the same, said tubular member being integrally formed with a plurality of rabble teeth depending therefrom, and releasable means for securing said tubular member on the supporting arm against relative rotary and longitudinal movement.

20 9. A furnace comprising a hearth, a vertically extending rotatable shaft at the middle of said hearth, arm members extending in substantially opposite directions over the hearth from said shaft transversely thereof, tubular members slidably received on said arms and embracing the same, said tubular members being integrally formed with a plurality of rabble teeth depending therefrom, the teeth on a member at the one side of the shaft being directed at an angle to move material being treated on the hearth toward the middle of the hearth, while the teeth on an opposite arm member are positioned at an angle to move material toward the periphery of the hearth, and releasable means for securing said first-named tubular member in respect

25 to the supporting arm.

10. A roasting furnace comprising a hearth confined within an insulating enclosure, electrically energized means for substantially uniformly heating said hearth throughout its area, rabbling means operating over said hearth, said heating means comprising a plate member carrying electrical resistance means and mounted over said rabbling means, said enclosure and said plate being provided

30 with communicating flue openings.

In testimony whereof we have signed our names to this specification.

EDITH MARY FOWLER,
Executrix of the last will and testament of
Edward J. Fowler, Deceased.
